UNITED STATES PATENT OFFICE.

ROBERT RUTHERFORD, OF REUTCHLER, AND THOMAS MOORE, OF O'FALLON,
ILLINOIS.

REVERSING-GEAR FOR ENGINES.

SPECIFICATION forming part of Letters Patent No. 352,489, dated November 9, 1886.

Application filed February 26, 1886. Serial No. 193,342. (No model.)

To all whom it may concern:

Be it known that we, ROBERT RUTHERFORD, of Reutchler, in the county of St. Clair and State of Illinois, and THOMAS MOORE, of 5 O'Fallon, St. Clair county, and State of Illinois, have invented a new and Improved Reversing-Gear for Steam-Engines, of which the following is a full, clear, and exact description.

The object of our invention is to provide a new and improved reversing-gear for steam-engines in which a positive motion is given to the slide-valve at all times, dispensing with the link now commonly used for reversing.

The invention consists of various parts and details and combinations of the same, as will be fully explained hereinafter, and then pointed out in the claims.

Reference is to be had to the accompanying drawings, forming a part of this specification, in which similar letters of reference indicate corresponding parts in all the figures.

Figure 1 is an end elevation showing our improvements. Fig. 2 is an end elevation 25 showing the reverse of Fig. 1. Fig. 3 is a sectional plan view on the line *xx*, Fig. 2. Fig. 4 is a sectional side elevation on the line *yy*, Fig. 3. Fig. 5 is a detail view of the locking mechanism. Fig. 6 is a face view of the under side of the cam-plate.

To the crank-shaft *A* of the steam-engine is secured a disk, *B*, having transverse recesses *B'* and *B''*, in which are placed the cleats *C'*, attached to the eccentric *C*. The latter is provided with the usual eccentric-straps and connections for moving the slide-valve of the engine, and with an elongated aperture, *C'*, through which the crank-shaft *A* passes without coming in contact with the eccentric *C* in whatever position the latter may assume on the disk *B*. The eccentric *C* is also provided with an extension, *C''*, in which is mounted the pin *D*, which is formed on its lower end with the prongs *D' D''*. In an aperture, *B''*, of the disk *B* is fitted, to slide longitudinally, the cam-plate *E*, having the diagonal slots or grooves *E'* on its upper side and the heart-shaped grooves *E''* on its lower side. The forked prongs *D' D''* of the pin *D* engage in the 45 grooves *E' E''* of the cam-plate *E*, and into the grooves *E'' E''* project the pins *F' F''*, secured

to the upper face of the locking-plate *F*, placed beneath the cam-plate *E*.

A wheel, *G*, having an aperture, *G'*, through which passes freely the crank-shaft *A*, is placed 55 on the outer ends of the cam-plate *E* and the locking-plate *F*. The cam-plate *E* has an elongated slot, *E'*, and the locking-plate *F* has an aperture, *F''*, through both of which apertures a pin or screw, *G''*, passes, which is secured to 60 the wheel *G*.

A plate, *H*, having a number of notches, *H'*, is secured by screws *H''* or other means to the eccentric *C*, and is placed across part of one face of the disk *B*, to which is also secured a 65 lug, *I*, (shown in detail in Fig. 6,) and provided with a spring-bolt, *J*, operated by a bell-crank, *J'*, against one arm of which the locking-plate *F* presses.

The cleats *C'* of the eccentric *C* are so arranged that when the eccentric is in its central position on the disk *B*, as shown in Fig. 1, the cleats are held in notches *K* in the disk *B* by a spring, *L*, placed in the recess *B'* of the disk *B*, and pressing against the upper edge 75 of the lower cleat, *C'*.

The operation is as follows: In the central position the eccentric *C* is locked on the disk *B*, as shown in Fig. 1, by means of the cleats *C'* being held in the notches *K* of the disk 80 *B*, and by the locking-bolt *J* being engaged with the middle notch, *H'*, of the plate *H*, so that when the shaft *A* operates the eccentric operates the slide-valve in the usual way without any lead. When it is desired to 85 reverse the engine, the wheel *G* is moved to or from the disk *B* by a lever or other device attached to the wheel *G* in any convenient manner. This movement of the wheel *G* carries the locking-plate *F* along at the same 90 time, which plate *F* receives a sidewise motion by the pins *F'* entering one side of the heart-shaped grooves *E'* of the cam-plate *E*, so that the edge of the locking-plate *F* presses against the bell-crank lever *J'*, which pulls 95 the bolt *J* downward and withdraws the same from the middle notch, *H'*, of the plate *H*. By this time the bolt *G''* of the wheel *G* has traveled to one end of the slot *E'* in the cam-plate *E*, and the latter, with the lock-plate *F*, 100 is carried along in the direction of the movement of the wheel *G*, whereby the eccentric

- C is moved sidewise on the disk B by the forked pin D, its prongs sliding in the diagonal grooves E of the cam-plate until the desired position for the eccentric C is attained.
- 5 The pressure on the wheel G is released, whereby the locking-plate F is forced to its former position in relation to the cam-plate E, as shown in Fig. 6, so that the spring-bolt J will enter one of the notches H' in the plate 45
- 10 H, which plate made the same side movement on the disk B as did the eccentric C. It will be seen that this sliding of the eccentric from its central position to one side of the disk B, attached to the shaft A, increases the throw 50
- 15 of the eccentric C, which consequently gives lead to the slide-valve, which does not open the ports of the cylinder as long as the eccentric C is in the central position, as shown in Fig. 1.
- 20 It will be understood that the movement of the wheel G to or from the disk B opens or closes the corresponding ports in the ends of the steam-cylinder by the sidewise motion of the eccentric C on the disk B.
- 25 Having thus fully described our invention, we claim as new and desire to secure by Letters Patent—
1. In a reversing gear for steam-engines, the combination of an eccentric provided with 30
- 30 a forked pin and adjustable on a disk attached to the crank-shaft, with a cam-plate sliding in the said disk and having diagonal grooves which engage with the said forked pin, substantially as herein shown and described.
- 35 2. In a reversing-gear for steam-engines, the combination of an eccentric provided with a forked pin and a notched plate and sliding on a disk attached to the crank-shaft, with a cam-plate having diagonal grooves, and with 40
- 40 a locking-plate operating a locking-bolt by means of a bell-crank lever, substantially as herein shown and described.
3. In a reversing-gear for steam-engines, the combination of an eccentric provided with a forked pin and a notched plate and sliding 45
- 45 on a disk attached to the crank-shaft, with a wheel provided with a pin, with a cam-plate having diagonal grooves, and with a locking-plate operating a locking-bolt by means of a bell-crank, substantially as herein shown and 50
- described.
4. In a reversing-gear for steam-engines, the crank-shaft A, the disk B, the eccentric C, the pin D, having the prongs D' D', and the plate H, having the notches H', in combination 55
- 55 with the wheel G, provided with the pin G', the cam-plate E, having the diagonal grooves E' E', the heart-shaped grooves E'', and the elongated slot E'', and a locking-plate, F, provided with the pins F' and operating the 60
- locking-bolt J by means of the bell-crank J', substantially as herein shown and described.
5. In a reversing-gear for steam-engines, the shaft A and a disk, B, having the grooves B' and B'', and the notches K, in combination 55
- 55 with the eccentric C, having the aperture C', and provided with the cleats C' C', and the spring L, substantially as herein shown and described.
6. In a reversing-gear for steam-engines, 70
- 70 the wheel G, provided with the pin G', and the locking-plate F, having the pin F', in combination with the cam-plate E, having the heart-shaped grooves E'' and the elongated slot E'', and the bell-crank J', operating the 75
- 75 locking-bolt J, substantially as herein shown and described.
